UNITED STATES PATENT OFFICE.

FRANK H. LINDNER, OF BLOOMFIELD, NEW JERSEY.

GRINDER.

1,132,196.

Specification of Letters Patent. Patented Mar. 16, 1915.

Application filed April 25, 1914. Serial No. 894,362.

To all whom it may concern:

Be it known that I, FRANK H. LINDNER, a citizen of the United States, and a resident of Bloomfield, in the county of Essex and State of New Jersey, have invented certain new and useful Improvements in Grinders, of which the following is a specification.

The invention relates to grinding apparatus, more particularly to a grinding tool 10 for the grinding of an internal cylindrical surface.

It has for its object a tool of this character which may be readily attachable to a 15 spindle, for example, for operation on a lathe of usual construction; or, which may be employed as a unit provided with its own driving means for direct attachment to the object to be ground.

20 The invention has for its object, furthermore, to enable the tool to be readily adjusted to the grinding of internal cylindrical surfaces of various diameters.

The nature of the invention will be best 25 understood when described in connection with the accompanying drawings, in which—

Figure 1 is a part longitudinal section of the tool, and cylinder to be ground thereby, as attached to a lathe. Fig. 2 is a trans- 30 verse section taken on the line *a*—*b*, Fig. 1. Fig. 3 is a transverse section taken on the line *x*—*x*, Fig. 1. Fig. 4 is an elevation, partly in section, illustrating a modifica- 35 tion.

Similar characters of reference designate corresponding parts throughout the several views.

Referring to the drawings, 1 designates a 40 face plate which is secured by means of its sleeve to a spindle 2 of a lathe, of which only the head 3 and said spindle are shown. The spindle may be rotated in the usual manner by a suitable motor or the like (not 45 shown). A shaft 4 passes through the said spindle and is mounted in suitable bearings therein and in the face plate 1, and is provided with a driving wheel 5. The latter may be connected with the driving mechanism 50 provided for spindle 2; or, may be rotated by suitable means (not shown) independently of the said spindle.

To the face plate 1 is secured a casing 6 having a cover 7 which may be integral therewith; or, the casing 6 may be made 55 integral with the face plate 1 and the cover

7 made removable, if desired, the whole constituting a suitable housing for the transmission mechanism between the driving shaft 4 and a driven shaft 13. To the cover 60 7 is pivotally attached, as upon an intermediate shaft 15 mounted in the face plate 1 and cover 7, a carrier member 8 for a quill 9 which carries the driven shaft 13 and at whose outer end is secured a grinding 65 wheel 14.

Power is transmitted from the shaft 4 to the shaft 13 through a gear wheel 10 secured to the inner end of the former and through two gear wheels 11 and 11' fixedly secured to 70 each other, or integral, and mounted to rotate upon the intermediate shaft 15 which is mounted in said casing and cover. Gear wheel 11' meshes with a gear wheel 12 fixed to the inner end of the driven shaft 13, and 75 which shaft passes through an arcuate slot 12' of the cover 7. The said gear wheel, shaft and quill may thus be swung about the intermediate shaft 15 as an axis to afford thereby a planetary movement of the said 80 shaft 13 and its grinder 14 about the intermediate shaft 15.

A locking bolt 16 is arranged to pass through a second arcuate slot 17 of cover 7; and by means of its head 18 and a nut 19, 85 is adapted to secure the carrier 8 to the cover 7 in any position selected and resulting from the planetary movement aforesaid. The grinding wheel, through the said planetary motion, may thus be adjusted for grinding the internal surfaces of hollow cylinders 90 of various diameters, the degree of adjustment depending upon the length of the planetary radii, degree of planetary position—angle between a line through the axis 95 of the intermediate shaft 15 and the axis of the driving shaft 4 and a line through the axes of the shafts 15 and 13, and upon the diameter of the grinding wheel 14. The grinding wheel may, therefore, be used substantially to its full capacity in that as it wears down the shaft 13 may be planetarily swung to compensate for its diminished diameter. The degree of the planetary position is arranged to be adjusted by means of 100 a nut 20 working on a threaded rod 21 secured to the cover 7, the said nut being held between downwardly extending fingers 22 of the carrier plate 8. It is understood, of course, that spindle 2 rotates the entire housing and with it the quill 9; and that the cylinder or similar object to be ground is to be 105 110 115

fed relatively to the said grinding wheel 14 by means (not shown) generally provided on a lathe in connection with its feed screw (not shown).

5. In Fig. 4, the grinder is shown as a complete unit, provided with suitable driving mechanism, and is adapted to receive the object to be ground. To this end, the spindle 2 is arranged to be held in a hub A concentrically to the internal cylindrical surface of the object which is suitably supported in arms or clamps R extending from the said hub. Spindle 2 is provided with a thread matching that of the hub A and carries a worm wheel N meshing with a worm M, the latter being on a shaft L driven through gears K and J and the latter of which is mounted upon shaft I driven through bevel gears F and H. Gear wheel F is mounted upon the shaft D of a driving motor B, said shaft D driving also a bevel gear wheel E in mesh with a bevel gear wheel G secured to the driving shaft 4 and which passes through the spindle 2. The motor B is suspended from a bearing O of spindle 2 by hangers C, C'. The driving shaft 4 is connected with the driven shaft 13 to drive the grinding wheel 14, as hereinbefore described; and the revolution of motor shaft D will rotate driving shaft 4 and simultaneously therewith the spindle 2, the former effecting the rotation of the grinding wheel 14 and the latter causing the same to be fed through the cylinder to be ground.
35. 1. In grinding apparatus: a driving shaft, and means to rotate the same; a driven shaft, and a grinding wheel secured thereon; means to revolve the driven shaft about an axis fixed relatively to the driving shaft; and planetary means for adjusting the length of the radius between the said shafts.
40. 2. In grinding apparatus: a driving shaft, and means to rotate the same; a rotatable housing mounted thereon; a driven shaft mounted in said housing, and a grinding wheel secured thereon; means retained and supported by said housing to transmit rotation from the said driving shaft to the said driven shaft; and means for varying the axial relation between said shafts.
45. 3. In grinding apparatus: a driving shaft in fixed position, and means to rotate the same; an intermediate shaft relatively fixed with respect to said driving shaft; a driven shaft; and a grinding wheel secured thereon; and transmission mechanism intermediate of said driving and driven shafts and affording a planetary movement of the latter about the said intermediate shaft.
50. 4. In grinding apparatus: a rotatable spindle, a housing secured thereto, a driving shaft passing through the spindle and into the housing, a gear wheel secured to the inner end of said driving shaft, a driven shaft extending from said housing, a gear wheel

secured to the inner end of driven shaft and a grinding wheel secured to its outer end, an intermediate shaft mounted in said housing, gear wheels rotatable with one another and rotatably mounted on said intermediate shaft, one of said gear wheels being in mesh with the said gear wheel on the driving shaft and the other in mesh with the said gear wheel on the driven shaft, a connecting member from and about the intermediate shaft to and about the driven shaft affording a planetary movement of the said driving shaft gear wheel and its driven shaft on and about the said gear wheel on the intermediate shaft.

5. In grinding apparatus: a rotatable spindle, a face plate secured thereto, a casing secured to said face plate, a driving shaft, an intermediate shaft mounted in said casing, a carrier pivoted thereon, a quill integral with said carrier, a driven shaft concentric with said quill, a grinding wheel secured to said driven shaft, transmission means intermediate of said driving and driven shafts, and means to secure said carrier in a selected position to said casing.

6. In grinding apparatus: a rotatable spindle, a face plate secured thereto, a casing secured to said face plate, a driving shaft passing through said spindle, an intermediate shaft mounted in said casing, a carrier pivoted thereon, a quill integral with said carrier, a driven shaft concentric with said quill, a grinding wheel secured to said driven shaft, transmission means intermediate of said driving and driven shafts, means for locking the carrier to the said casing and including a locking bolt adapted to pass through an arcuate slot of the casing, a head on said locking bolt adapted to bear against the casing, and a nut on said locking bolt to bear against said carrier.

7. In grinding apparatus: a rotatable spindle, a face plate secured thereto, a casing secured to said face plate, a driven shaft, an intermediate shaft mounted in said casing, a carrier pivoted thereon, a quill integral with said carrier, a driven shaft concentric with said quill, a grinding wheel secured to said driven shaft, transmission means intermediate of said driving and driven shafts, means to secure said carrier in a selected position to said casing, and means to adjust said carrier relatively to said casing.

8. In grinding apparatus: a rotatable spindle, a face plate secured thereto, a casing secured to said face plate, a driving shaft passing through said spindle, a casing secured to said face plate, an intermediate shaft mounted in said casing, a carrier pivoted thereon, a quill integral with said carrier, a driven shaft concentric with said quill, a grinding wheel secured to said driven shaft, transmission means intermediate

ate of said driving and driven shafts, means for locking the carrier to the said casing and including a locking bolt adapted to pass through an arcuate slot of the casing, a head on said locking bolt adapted to bear against the casing, a nut on said locking bolt to bear against said carrier, and means to adjust said carrier relatively to said casing and comprising fingers extending downwardly from said carrier, a threaded rod secured to

the cover, and a nut thereon between said fingers.

Signed at Newark, in the county of Union, and State of New Jersey, this 21st day of April, A. D. 1914.

FRANK H. LINDNER.
